UNITED STATES PATENT OFFICE.

ALBERT L. CRAMER, OF DENVER, COLORADO.

ADJUSTABLE ARCH SUPPORT.

Application filed October 31, 1924. Serial No. 747,001.

To all whom it may concern:

Be it known that I, ALBERT L. CRAMER, a citizen of the United States, residing at the city and county of Denver and State of Colorado, have invented certain new and useful Improvements in Adjustable Arch Supports; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to improvements in adjustable arch supports of the type described and claimed in my copending application, Serial No. 688,967, filed January 28, 1924.

20 In the application referred to, I have shown and described an adjustable elastic band arch support having two pockets for the reception of felt pads, one pocket opening longitudinally of the band and the other opening transversely thereof. This is a very satisfactory support, but I find that the treatment of the various defects of the human foot require adjustments that cannot very well be made with the device shown 25 and described in the application referred to. I have therefore invented a new device of the same general character, which differs from my previous invention in particulars that permit it to be more readily adjusted 30 to the shape and condition required. It is well known to those who are familiar with the treatment required by the class of defects which this device is intended to remedy, that very small, and to the uninitiated, 35 apparently insignificant, changes in the construction often makes it possible to successfully remedy defects which could not have been remedied unless accurate adjustment had been possible.

40 I have found that the use of felt pads alone are not sufficient to enable all the required adjustment to be made. I have found that, if, in addition to the felt pads, I employ hair which can be inserted into a separate pocket in any required amount, and which can be distributed in various ways so as to produce the results required, I am able to obtain better results.

45 My present invention, briefly described, 50 consists of an elastic band which completely

encircles the foot and which has a transversely opening pocket of non-elastic material secured to its outer surface and adapted to receive felt pads, and a second pocket on the inside for the reception of hair. These 60 pockets are, preferably, located one over the other so that the contents of each will modify that of the other.

My invention can be most clearly explained and will be most readily understood 65 when reference is had to the accompanying drawing, in which the preferred form thereof is shown, and in which:

Fig. 1 is a perspective view of my improved support; 70

Fig. 2 is a section taken on line 2—2, Fig. 1;

Fig. 3 is a section taken on line 3—3, Fig. 2;

Fig. 4 is a perspective view of the support, 75 but looking in the opposite direction from the view shown in Fig. 1; and

Fig. 5 is a side elevation of a foot showing the band in place thereon.

The support consists of an elastic band 6 80 whose ends are joined at 7 so as to form a ring. Secured to the outer surface of the band is a piece of non-elastic webbing 8 which is stitched to the band 6 on both sides and to the rear so as to form a substantially 85 rectangular pocket open towards the front of the foot. Within the pocket I place felt pads 9 to the thickness required. To the inside of the band and directly over the piece 8, I secure another piece of similar 90 webbing 10 of substantially the same size as 8. This webbing is sewed to the band at its ends and along the front edge where the seam has been designated by numeral 11. Along the front edge the piece 10 is sewed 95 to the web part way so as to secure it thereto to the point marked 12 in Fig. 4. This leaves a small opening through which the hair 13 may be inserted and properly distributed throughout the pocket. The proper 100 distribution of this hair is important, as it is thereby that the best results are obtained.

By having the upper pocket open at one point and stuffed with hair, the coarse adjustment may be made by means of the felt 105 pads, while the finer adjustments are made by means of the hair, which can be inserted in such amounts and distributed in such a manner that a comfortable and effective arrangement will be secured.

Having now described my invention, what I claim as new is:

An arch support comprising, in combination, an elastic band adapted to encircle the foot, said band being adapted to exert a contracting force on the foot, a pocket, formed in part of non-elastic material, on the underside of said band, said pocket being open towards the front and adapted to receive a

felt pad, a second pocket, also formed in part of non-elastic material, located directly over the first pocket, on the inside of the band, said second pocket having an opening thereinto from the rear of the band, whereby hair may be inserted thereinto and distributed therein.

In testimony whereof I affix my signature.

ALBERT L. CRAMER.
